SPRING EJECTOR FOR METAL PUNCH
William F. Reece, Detroit, Mich., assignor to Allied Products Corporation, Detroit, Mich., a corporation of Michigan

Filed Apr. 15, 1960, Ser. No. 22,558
2 Claims. (Cl. 83—128)

The present invention broadly pertains to punching dies and more particularly to an improved ejector for removing the cutout slug or core from the cutting face of a punching die.

In punching dies of the general type herein described various means have been employed to eject the cutout slug or core from the cutting face of the punching die at the completion of each punching stroke. Ejection means of the plunger type axially disposed in the punching die are conventionally comprised of a plurality of parts which are specifically designed for a particular punching die and are of limited interchangeability. In addition, the punching dies incorporating such ejector plungers are conventionally comprised of a plurality of assemblable and disassemblable sections which must be accurately machined to accommodate the ejector means and require the punching die to be assembled and disassembled each time the ejector means are replaced or the punching die sharpened. Because of these factors ejector-type punching dies heretofore known have been costly to manufacture and are tedious and time consuming to repair.

It is the principal object of the present invention to provide a unique unitary resiliently biased ejector that is simply accommodated in a unitary punching die enabling quick and simple installation and removal thereof.

Another object of this invention is to provide an ejector that is readily modified for use in punching dies of varying lengths thereby substantially increasing the interchangeability thereof.

Still another object of this invention is to provide a punching die incorporating therein a unique ejector that is of simple design, durable operation, and inexpensive to manufacture.

The foregoing and other objects of this invention are achieved by an ejector characterized by a helical coil spring disposed in an axial bore in the punching die and having a straight wire shank portion integrally connected thereto extending axially through a small bore through the tip of the die and projecting beyond the cutting face surface thereof so as to contact and resiliently eject a cutout core or blank from the cutting face of the die at the completion of each punching stroke.

Other objects and advantages of the present invention will become apparent from the following detailed description taken in conjunction with the accompanying drawing which is a vertical fragmentary sectional view of a typical punch and die set installed in a suitable press and illustrating in particular a novel ejector incorporating the preferred embodiments of this invention.

As shown in the drawing a cylindrical punching die 2 comprising a cutting tip portion 4 having a cutting face 5 at the end thereof and a cylindrical shank portion 6 is removably disposed in a central bore 8 of a punch retainer or holder 10 which is detachably secured to a movable slide or ram 12 of a punch press. The punch holder 10 is comprised of a base pad 14 fixedly secured to a block member 16 having an angularly disposed bore 18 therein communicating with the central bore 8. Resiliently biased engaging means comprising a coil spring 20 and a ball 22 are disposed in the angular bore 18 whereby the periphery of the ball 22 is disposed in engaging contact with a teardrop shaped groove 24 in the periphery of the shank portion 6 preventing inadvertent withdrawal

2

thereof from the punch holder 10. The punching die 2 may be simply released from the punch holder 10 by inserting a suitable release pin (not shown) upwardly through an aperture 26 in the block member 16 adjacent to the central bore 8 and in communication with the angular bore 18 whereby the ball 22 is pushed upwardly in opposition to the coil spring 20 and out of engagement with the groove 24 enabling the withdrawal of the shank portion 6 from the central bore 8. When the punching die 2 is installed in the punch holder 10 as shown in the drawing, end surface 28 of the shank portion 6 is in firm abutting relationship with the base pad 14.

The punching die 2 is shown in the drawing in the lowered position wherein the end of the cutting tip portion 4 thereof is disposed in sliding contact in a bore 30 in a lower die 32. The lower die 32 is removably secured in a suitable die holder 34 similar to punch holder 10 that is provided with a coil spring 36 and a ball 38 which engages a groove 40 in the periphery of the die 32. The die holder 34 is detachably and adjustably secured to a bolster or bed 42 of the press. As shown in the drawing the lower die 32 is provided with a counter bore 44 in axial alignment with the bore 30 and in communication with a bore 46 through the bed 42 providing therewith an ejection chute for discharging the slugs or cores 48 punched out of the sheet material 50.

At the completion of the downward stroke of the punching die as shown in the drawing, the core 48 is removed from the cutting face 5 of the punching die by a unique ejector 51 comprising the present invention. The ejector 51 is comprised of a coiled wire or spring portion 52 and a straight wire tang 54 extending from the center of and in axial alignment with the coiled wire portion 52. The straight tang 54 is slidably disposed and reciprocable in a bore 56 extending axially through the cutting tip portion 4 of the punching die 2 and projects beyond and substantially perpendicular to the cutting face 5. The tang 54 should be closely fitted in the bore 56 so as to provide sufficient clearance therebetween to enable guided sliding movement and prevent lateral deflection of the tang under load which might tend to cause binding. The coiled wire portion 52 is comprised of closed or nested coil sections 58 and an open coil section 60 which provides axial resiliency and enables axial movement of the straight tang 54 integrally connected to and axially extending from the lower portion thereof. The nested coil sections 58 and the open coil section 60 are guidably and slidably disposed in a central bore 62 extending through the punching die 2 and disposed in axial alignment and in communication with the bore 56 through the cutting tip portion 4 of the punching die.

The upper end of the ejector 51 is seated against the base pad 14 of the punch holder 10 and is of a plain end or can be squared by closing and/or grinding for better seating characteristics. The lower end of the coiled wire portion 52 of the ejector 51 is seated on an annular shoulder 64 at the base of the central bore 62 which limits the downward axial sliding movement of the tang 54.

The free length of the coiled wire portion 52 of the ejector can be simply controlled by varying the length of the open coil section 60 and preferably by cutting off a portion of the upper end of the closed coil section 58 which enables an ejector of a given coil diameter to be adapted to punching dies having shanks of various lengths. For any given punching die it is preferred that the free length of the coiled wire portion 52 of the ejector 51 exceeds the length of the central bore 62 whereby the open coil section 60 will be in compression when installed in the punching die. The length of the tang 54 of the ejector 51 may be cut to any desired length depending on the length of the cutting tip portion 4 of a particular punching die so when in the fully projected position as

limited by annular shoulder 64 a small portion thereof will project beyond the cutting face 5 of the punching die. It will of course be appreciated by those skilled in the art that the open coil section 60 is designed to provide sufficient axial deflection between the open position and a nested compressed position to enable the projecting end portion of the tang 54 to completely retract within the cutting tip portion 4. It is also preferred that the open coil section 60 be disposed intermediate the ends of the coiled wire portion 52 of the ejector providing a short nested coil section 58 at the lower end thereof from which the tang 54 axially extends. The short nested coil section 58 adjacent to the tang 54 is substantially rigid and serves as a sliding guide bearing assuring continuous accurate alignment of the upper portion of the tang with the bore 56 thereby minimizing binding between the tang and bore 56 during the sliding movement of the tang.

When the punching die 2 is withdrawn from the punch holder 10 the ejector 51 can be simply and quickly removed by sliding it out. Accordingly, the punching die 2 may be sharpened or the ejector replaced without the necessity, as has been heretofore practiced, of first disassembling the punching die to remove the ejector means. After the cutting face of the punching die has been ground the end of the tang 54 may be recut or ground to the desired length.

In operation, when the punching die comes in contact with the sheet material 50 during the downward punching stroke of the slide 12 as viewed in the drawing, the end of the tang 54 is forced upwardly through the bore 56 until it is flush with the cutting face 5 thereby partially compressing the open coil section 60. After the cutting tip portion 4 of the punching die has perforated the sheet material 50, the upward force against the tip of the tang 54 is released whereby the open coil section 60 axially biases the tang 54 downwardly separating the slug 48 from the cutting face 5 of the punching die as shown in the drawing.

It will of course be appreciated by those skilled in the art that the ejector hereinabove described in relation to the specific perforating punch shown in the drawing is equally applicable to other types of punching dies, blanking dies and the like wherein one or more ejectors may be incorporated for separating the cutout slug or core from the cutting face of the punch. Accordingly, while the preferred embodiment herein described is well calculated to fulfil the objects above stated, it will be appreciated that the invention is susceptible to modification, variation and change without departing from the proper scope of fair meaning of the subjoined claims.

What is claimed is:

1. In a punching die including a body member having a cutting face thereon, a portion of the body member defining a first bore extending inwardly a distance from the surface opposite to the cutting face and a second bore extending inwardly from the cutting face and disposed in axial end communication with the first bore, the improvement comprising an ejector disposed in the first and second bores for ejecting a cutout slug from the cutting face of the die, said ejector comprising a helical coil spring portion removably disposed in the first bore and a straight tang extending axially from and integrally affixed to one end of said coil spring portion, said tang slidably disposed in the second bore and resiliently reciprocable therein to and from a projected position wherein the end of said tang projects a distance beyond the cutting face and a retracted position within the die.

2. In a punching die including a body member having a cutting face thereon, a portion of the body member defining a first bore extending inwardly a distance from the surface opposite to the cutting face and a second bore extending inwardly from the cutting face and disposed in axial end communication with the first bore, the improvement comprising an ejector disposed in the first and second bores for ejecting a cutout slug from the cutting face of the die, said ejector comprising a helical coil spring portion removably disposed in the first bore and a straight wire tang extending axially from and integrally affixed to one end of said coil spring portion and slidably disposed in the second bore, said coil spring portion comprising at least one nested coil section disposed at each of the ends thereof and at least one open coil section disposed intermediate the end of said nested coil sections, said open coil section providing for axial resilient reciprocation of said tang in the second bore to and from a projected position wherein a portion of said tang projects a distance beyond the cutting face and a retracted position wherein said tang is retracted within the die.
